(57) **CLAIM**

The ornamental design for an automobile body, as shown and described.

DESCRIPTION

FIG. 1 is a front perspective view of an automobile body showing our new design;

FIG. 2 is a rear perspective view thereof;

FIG. 3 is a front view thereof;

FIG. 4 is rear view thereof;

FIG. 5 is a left side view thereof;

FIG. 6 is right side view thereof; and,

FIG. 7 is a top view thereof.

It will be understood that the broken lines shown in the drawings illustrate portions of the automobile body that form no part of the claimed design.

1 Claim, 6 Drawing Sheets
